OVEREDGE SEWING MACHINE
CONSTRUCTION

Ned L. Wallenberg and Albert M. Schweda, Chicago, Ill., assignors to Union Special Machine Company, Chicago, Ill., a corporation of Illinois

Application January 24, 1949, Serial No. 72,312

10 Claims. (Cl. 112—162)

1

This invention relates to sewing machines of the overedge type adapted to provide either a two-thread or a three-thread stitch at and around the edge of work advanced along a flat supporting surface.

Machines of the foregoing character have heretofore been of two major types, i. e., of the straight needle type having a rectilinearly movable needle bar and of the curved needle type having a needle carrier that is oscillated about an axis transverse to the line of stitch formation. The straight needle type is generally recognized as best suited for the stitching of relatively heavy work while the curved needle type is considered best suited for the stitching of relatively light fabrics.

A primary object of the present invention has been to provide a construction which may be readily adapted for either a straight needle or a curved needle. Toward this end a special frame has been devised which is readily separable along a horizontal plane to divide the same into two major components, i. e. a lower or base member and an upper needle carrying member. Moreover, the arrangement is such that a single base member is adapted to be connected with either an upper member having a reciprocating straight needle or one having an oscillating curved needle carrying arm. This enables the user of the machine to employ interchangeably at different times, depending upon the character of the work to be perforated, the desired type of upper member. It also enables the manufacturer to reduce production costs since the base members may be produced in larger quantities for assembly with the selected upper member.

In attaining the foregoing purposes a feature of the new machine is the provision of a base member which is separable from the upper member along a plane below the level of the work support.

A further novel feature of the invention is the provision of a rotary shaft in the base member of the character indicated which serves to drive certain stitch forming and work feeding devices carried by said member.

Another novel feature is the provision of at least one rock shaft in the upper member of the machine connected for operation by the rotary shaft in the base member for cooperation with the stitch forming means and disposed at least in part below the level of the work supporting surface. This contributes importantly to the interchangeable use of the base member with either of the types of upper member hereinabove mentioned.

2

Other objects, features and advantages of the invention will appear from the detailed description of an illustrative form of the invention which will now be given in conjunction with the accompanying drawings, in which:

Fig. 1 is a vertical section taken along the axis of the main driving shaft of a machine, made in accordance with the invention, equipped with a curved needle;

10 Fig. 2 is a horizontal section through the machine, taken along the line 2—2 of Fig. 1;

Fig. 3 is a transverse vertical section through the machine along the line 3—3 of Fig. 1;

15 Fig. 4 is a front elevational view of the machine with a part of a front cover member broken away;

Fig. 5 is a front elevational view, with parts broken away, showing the machine with a different upper structure having a reciprocating, straight needle;

Fig. 6 is a top plan view of the machine as shown in Fig. 5;

Fig. 7 is an end elevational view of the machine as seen from the right end of Fig. 5;

25 Fig. 8 is an end elevational view of the machine as seen from the left end of Fig. 5, with a cover member removed from the needle head of the machine;

Fig. 9 is a vertical sectional view through the machine as shown in Fig. 5, taken along the axis of the main driving shaft;

30 Fig. 10 is a horizontal sectional view taken along the line 10—10 of Fig. 9; and

Fig. 11 is a partial vertical section taken along the line 11—11 of Fig. 10.

35 Referring now to Figs. 1 to 4 of the drawings, there is illustrated a curved needle overedge sewing machine of the type more fully disclosed in the pending application of Ned L. Wallenberg and George Sauer, Serial No. 63,924 filed December 7, 1948. For further details as to the construction and operation of the machine, reference may be had to said pending application.

40 The illustrative machine comprises a frame for supporting the operating mechanism and for largely enclosing the parts requiring lubrication. This frame includes a base plate 10 on which is mounted a lower member 11 of the vertical wall structure. A suitable gasket is preferably provided between the base plate 10 and the lower edge of the member 11. Parts 10 and 11 may together be considered the base portion of the machine. Above the member 11 a second vertical wall member 12 is provided, this being separable from the lower member along the line 13 (Fig. 1). This line of separation, as will be seen, is

somewhat below the work supporting surface of the machine so that certain parts may be supported by the upper member at points below said surface. Members 11 and 12 are secured together by screws 14 (Figs. 2 and 3) which pass upwardly through laterally extending flange portions of the two members. A top closure member 15 is provided above the upper edge of the member 12 and the juncture between these members is sealed by a suitable gasket 16. Screws (not shown) may be provided for retaining the top 15 on the member 12. As will be seen, the parts 10, 11, 12 and 15 serve to provide an enclosed chamber adapted to retain lubricant 17 which, as will later appear, is automatically distributed through the housing for the lubrication of the moving parts. An extension 18 at the left end of the member 11 provides a further, substantially enclosed chamber surrounding certain of the stitch forming devices and work feeding means. A bracket 19 carried by the extension 18 provides a part of the enclosure for the left end of this second chamber. A work supporting plate 20, which as explained in said pending Wallenberg, et al. application is pivotally mounted upon a vertical axis, may be swung either into its active position shown in Fig. 1 or into an inactive position in which access is provided to certain of the stitch forming and work feeding devices.

A main driving shaft 21 passes horizontally through the enclosed chamber of the machine and extends beyond each end, as shown in Fig. 1. At its right end the shaft carries a combined handwheel and pulley 22. The shaft is journaled at this end in needle bearings 23 carried by a sleeve 24 fitted in an opening in the wall of member 11 and having a radially extending flange 25 adapted to receive screws 26 for securing the sleeve to the frame. Adjacent its opposite end the shaft 21 is journaled in a split bushing 27 held in assembled relation by means of a sleeve or ferrule 28. Bushing 27 is of such a diameter that it enables the introduction of the shaft into the frame from the left in Fig. 1.

Shaft 21 is provided with a series of eccentric or crank portions adapted for connection with the various devices to be driven. One of these crank portions is surrounded by a strap 29 having an integrally connected pitman 30 which is pivotally attached to a split sleeve 31 clamped to the inner end of a rock shaft 32. This shaft is journaled in needle bearings 33 and 34 mounted in an opening extending through a boss formed on the upper member 12 of the frame. To the outer end of the shaft 32 there is secured an arm 35 which carries a curved needle 36. It will be noted that the axis of the shaft 32 is only slightly below the work supporting surface 20, so that as the shaft is rocked upon the rotation of shaft 21 the needle will be carried into the work along a substantially vertical line.

Cooperating with the needle is an under looper and an overedge looper. A spherical crank portion 37 on the shaft 21 cooperates with a strap 38 at the upper end of a pitman 39, the lower end of which carries a strap 40 cooperating with a ball-pin 41 mounted in a rock arm 42. The latter, as more clearly shown in the pending Wallenberg, et al. application, is mounted on a transversely extending shaft 43 (Figs. 1 and 4) which, at its forward end carries an under looper 43a (Figs. 2 and 4). Another spherical crank portion 44 of the shaft 21 cooperates with a strap 45 at the upper end of a pitman 46 having at its lower end a strap 47 cooperating with a ball

pin projecting from a shaft 48. The latter, through the connections more fully disclosed in said pending Wallenberg, et al. application, serves to drive an overedge looper 48a (Figs. 2 and 4). This looper is pivotally connected at its lower end with an arm 48b, secured to the shaft 48, and at an intermediate point with a rock arm 48c. The details of the stitch forming mechanism are more fully disclosed in said pending Wallenberg, et al. application.

The devices for feeding the work in relation to the stitch forming means are driven by a spherical eccentric portion 49 of the shaft 21 which cooperates with a strap 50 at the forward end of a pitman 51. The other end of the latter is connected by a strap 52 with the ball portion (not shown) of a pin 53 adjustably secured in an arcuate slot 54 formed in an arm 55 secured to a rock shaft 56. This extends parallel with the shaft 21 and is journaled at its right end in a sleeve 57 carried by a lug or web integral with the frame and is journaled at its left end in a sleeve 58 mounted in a boss at this end of the frame. A vertically disposed feed rocker 59 is secured to the shaft 56 adjacent its left end. This rocker is bifurcated at its upper end to provide bearing members 59 and 60 for a stud 61 to which is secured a sleeve 62 formed at the rearward end of a feed bar 63. At its forward end the feed bar carries a feed dog 65 which is given a 4-motion movement to advance the work. An auxiliary feed dog 66 is given a differential feed movement in relation to the main feed dog. This auxiliary feed dog is carried by a bar 67 secured to a rod 68 slidably mounted in spaced bearings 69 and 70 provided on the feed bar 63. Intermediate the bearings 69 and 70 there is secured to the rod 68 a block 71 having an outwardly projecting pin 72 to which is connected the forward end of a link 73. At its opposite end this link is connected with a stud 74 capable of adjustment in an arcuate slot provided in a plate 75 secured to or formed integral with the feed rocker. By varying the position of the stud 74 in the plate 75 the auxiliary feed dog may be given either greater or smaller movements than the main feed dog. Lifting and lowering movements are imparted to the feed dogs by an eccentric portion 76 at the left end of the shaft 21 (Fig. 1). This eccentric portion cooperates with blocks 77 slidably longitudinally on the feed bar but held against vertical movement in relation thereto.

A presser foot 77a (Fig. 4) carried by a vertically slidable bar 77b, mounted in a head at the end of an arm 77c extending from the upper frame member 12 to a point over the stitching point, is urged downwardly against the work support by a spring 77d to cooperate with the feed dog in advancing the work.

Means are also provided for trimming the edge of the work in advance of the stitch forming means. For this purpose a strap 78 at the lower end of a pitman 79 cooperates with a crank or eccentric portion of the shaft 21. At its upper end the pitman carries a strap 80 which cooperates with a ball pin 81 extending from an arm 82 (Figs. 2 and 3). This arm has a hub at its opposite end in the form of a split sleeve 83 clamped about a rock shaft 84 journaled in needle bearings 85 and 86 which are mounted in an opening extending through the left hand wall of the member 12 of the frame. Shaft 84 is parallel with and adjacent the shaft 32, as shown in Figs. 2 and 3. At its outer end, shaft 84 has secured thereto an arm 87 which carries a movable trim-

mer blade 87a (Fig. 4) adjustably retained by a screw 87b and collar 87c, as more fully disclosed in said pending Wallenberg, et al. application.

It will be understood that the machine of Figs. 1 to 4 is provided with other accessory devices, including suitable thread handling and tensioning means and means for effecting automatic lubrication of the operating parts. The latter includes a disc 88 of slightly cup-shaped form secured by a hub 89 to a concentric portion of the shaft 21. Disc 88 dips into the lubricant 17 and serves to whip this into a spray within the enclosed housing to effect the desired lubrication of the operating parts both within the housing and exterior thereof.

Turning now to Figs. 5 to 11 inclusive, there is shown a straight needle type of overedger having the same construction as the machine of Figs. 1 to 4 in its lower portion, but having a different top construction. It comprises a frame having a base plate 90 secured in any suitable way to a lower frame member 91. A gasket may suitably be employed to effect a tight seal between these parts. An extension 91a (Figs. 8 and 9) of the lower frame member has an upwardly extending part 91b provided with a lug 91c on which is pivotally mounted a work supporting member 91d. An upper frame member 92, separable from the lower member along the line 93 (Figs. 5, 9 and 11) is secured to the lower member by means of a series of screws 94 (Fig. 11). A gasket may, if desired, be provided between the members 91 and 92. Member 92 is provided with a short, horizontally extending, overhanging arm 95 having a partition 96 separating the main enclosure of the machine from a needle head portion 97. The latter is closed at its outer end by a removable cover 97a (Figs. 5 and 9).

A main drive shaft 98 is provided in the member 92. This shaft extends longitudinally of the overhanging arm from a point exterior of the frame to a point within the needle head. A combined handwheel and pulley 99 is secured to the outer end of the shaft for driving the same. Shaft 98 is journaled adjacent the pulley in needle bearings 100 carried by a bearing sleeve 101 having a radially extending flange 102 secured by screws 103 to the wall of the member 92. In the partition 96, a pair of needle bearings 104 is provided for journaling the opposite end of the shaft 98 adjacent the needle head. The shaft carries a balanced crank 105 connected by a link 106 with a pin 107 projecting laterally from the needle bar 108. The latter is mounted for longitudinal reciprocation in a bearing sleeve 109 mounted in the bottom of the needle head. A needle 110 is secured to the needle bar and is reciprocated by the latter to and through the work support for the formation of stitches. As best shown in Fig. 8, the needle bar is inclined at a small angle, of say 15°, to the vertical to cooperate advantageously with the under looper and overedge looper to be hereinafter described. Secured to the link 106 is a thread take-up arm 111 arranged to cooperate with a fixed guide 112 and a thread tensioning device 113 for controlling the needle thread.

Also mounted in the needle head is a presser bar 114 adapted for longitudinal reciprocation in grooves provided at the top and bottom portions of the needle head. The grooves are closed by the needle head cover which serves to prevent lateral movement of the bar 114. The presser bar is disposed adjacent to the needle bar and is parallel therewith. At its lower end it carries a presser foot 115 which is connected with the bar

by means of a flat spring element 116. The foot is adapted to rock about a knife edge 117 provided at the forward end of an arm 118 carried by the presser bar. Spring 119 (Fig. 9) cooperating with a lug 120 extending laterally from the presser bar serves to urge the latter downwardly to force the presser foot against the work. At its upper end the spring 119 cooperates with a block 121 secured to the lower end of an adjustable screw 122. The tension of the spring may be varied by turning the knurled head of the screw.

Lifting of the presser bar, to release the work and permit the introduction of new work is brought about by an arm 123 secured to a rock shaft 124 mounted in a rearwardly extending lug 125 on the needle head. Arm 123 extends beneath a pin 126 projecting laterally from the presser bar and, through the latter, serves to lift the presser bar when the arm is rocked counterclockwise (Fig. 8). An arm 127 at the opposite end of shaft 124 has an eye 128 at its outer end adapted to be connected by a rod or chain with a foot treadle or the like for rocking the shaft 124 and the arm 123 to lift the presser bar. This lifting mechanism is normally held in inactive position by means of a spring 129 which urges arm 123 and the connected parts in a clockwise direction until the upper end of a slot 130 engages a pin 131 on the lug 125.

Within the enclosed housing of the frame there is secured to the shaft 98 a gear 132, this having a hub which is fastened by screws 133 to the shaft. Meshing with gear 132 is an idler gear 134 mounted for free rotation on a stationary shaft 135. A gear 136, having a hub secured by screws 136a to a shaft 137 in the lower portion of the machine, meshes with the idler gear 134 and is rotated thereby. Shaft 137 is journaled in needle bearings 138 carried by a sleeve 139 having a radially extending flange 140 secured by screws 141 to the right wall of the lower member 91 (Fig. 9). Adjacent its opposite end the shaft 137 is journaled in a bushing 143 which is of split construction and retained in assembled relation by a sleeve or ferrule 144. A screw 144a (Fig. 10) serves to retain the ferrule and bushing against rotation.

Just to the right of the bushing 143 shaft 137 is provided with a spherical crank portion 145 cooperating with a strap 146 at the upper end of a pitman 147 the lower end of which is connected by a strap 148 with a ball pin 149 carried by an arm 150. (Figs. 9, 10, and 11.) Arm 150 is bent laterally, as shown in Fig. 11, and is provided at its end with a hub 151 secured by screws or the like to a rock shaft 152. (Figs. 5 and 9.) To the forward end of the shaft 152 is secured an under looper 153 (Fig. 5).

To the left of the bushing 143 (Fig. 9) there is another spherical crank portion 154 of the shaft 137 which cooperates with a strap 155 at the upper end of a pitman whose lower end is connected by a strap 156 with a ball pin 157 extending laterally from a rock shaft 158. This rock shaft, as shown in Fig. 5, carries at its forward end an arm 159 pivotally connected with the lower end of a substantially L-shaped overedge looper 160. At the elbow of this looper it is pivotally connected by a stud 161 with an arm 162 adapted to be rocked about a pivot 163. It will be understood that the driving connections are such that the needle and the two loopers are operated in properly timed relation to form an overedge stitch. When this is of the three-thread type, the underlooper passes its thread through

the needle thread loop as the needle projects downwardly through the work, and subsequently the overedge looper passes its thread through the loop of the under-looper thread and carries it over the edge of the work to a point in the path of the needle, as shown in Fig. 5. Upon the subsequent downward movement of the needle its thread is carried through the loop of the over-edge thread and the stitch is completed. Suitable thread controls are provided for insuring the formation of the desired type of stitch. If a two-thread stitch is desired, the overedge looper may be in the form of a spreader instead of a thread carrying member and this will carry the loop of the underlooper thread around and over the edge of the work into the path of the needle. This, of course, applies to the curved needle construction as well as the straight needle construction.

Returning to Fig. 9, another eccentric or crank portion of the shaft 137 cooperates with a strap 164 at the lower end of a pitman 165 which has a strap 166 at its upper end surrounding a pin 167 extending laterally from an arm 168. The latter has a split hub 169 which is clamped to a rock shaft 170 journaled in needle bearings 171 and 172 in a boss carried by the upper member 92 of the frame. Shaft 170 corresponds with shaft 84 of Fig. 2 and has its axis below the work supporting surface. An arm 173 secured to the outer end of the shaft 170 extends forwardly in a substantially horizontal direction (Fig. 8) and carries at its forward end a head 174 to which is secured, by means of a screw and collar 175 (Figs. 5 and 8) a blade 176. The latter is of inverted L-shape in cross-section and is adjustable longitudinally to bring it into proper cooperation with a stationary trimmer blade 177 carried by the base member 91. For further details as to the construction and operation of the trimmer mechanism reference may be had to said pending Wallenberg, et al. application.

Adjacent the gear 136 a spherical eccentric portion 178 is provided on the shaft 137. This cooperates with a strap 179 at the forward end of a pitman 180 having a strap at its other end cooperating with a ball pin 181 which may be set in any desired position along an arcuate slot 182 in an arm 183 secured to a rock shaft 184 (Figs. 10 and 11). Shaft 184 has secured thereto, adjacent its opposite end, a feed rocker 185 having upstanding bearing lugs 186 and 187 in which is journaled a stud 188. Secured to the latter between the upstanding lugs is the hub 189 of a feed bar 190. The latter at its forward end carries a feed dog 191. An auxiliary feed dog 192 secured to an arm 193 is carried by a slide rod 194 mounted in laterally projecting lugs 195 and 196 of the feed bar. Intermediate these lugs there is secured to the rod 194 a block 197 having a laterally extending pin connected by a link 198 with a bolt 199 adjustably mounted in an arcuate slot (not shown) in a plate 200 integral with the lug 187 of the feed rocker. By appropriate adjustment of the bolt 199 in the plate 200 the stroke of the auxiliary feed dog may be varied to make it either greater or less than that of the main feed dog 191. Lifting and lowering movements are imparted to the feed dogs by an eccentric or crank portion 201 at the left end of the shaft 137 (Fig. 9) which cooperates with blocks 202 carried by the feed bar. These blocks are slidable longitudinally of the feed bar, but are retained against transverse vertical and horizontal movement with respect thereto.

Various auxiliary devices, such as tread tensioning, guiding and controlling means, means for delivering lubricant to various points outside of the main enclosed chamber, and the like are, of course, provided. Since the details of these form no part of the invention to be claimed herein, they need not be further described. They may be of any suitable and known form.

It will be noted that the lower portion of the machine illustrated in Figs. 5 to 11 inclusive, is identical with that of the machine illustrated in Figs. 1 to 4 inclusive, except for the omission of a few parts and the addition of several parts. For example, the needle carrying rock shaft and the operating means therefor, provided in the machine of Figs. 1 to 4 are omitted from the machine of Figs. 5 to 11. The gear 136 on the other hand, provided in the machine of Figs. 5 to 11 inclusive, is omitted from the machine of Figs. 1 to 4. It will be understood that these parts may, if desired, be provided in the lower portion of the machine, regardless of the type of upper structure employed, and they may simply be left idle when the selected upper structure has no need for them. The substitution of one upper structure for the other may be readily effected by simply disconnecting and reconnecting the pitman serving to drive the rock shafts for the movable trimmer element and the curved needle and by disconnecting the applied upper frame member from the lower frame member, through the removal of the screws (14 or 94) and the substitution of the other upper frame member. The driving pulley and handwheel is preferably also shifted although, if desired, it may be left on the lower rotary shaft regardless of the upper frame member employed. Thus a single base structure may be readily used interchangeably with either a curved needle or a reciprocating, straight needle upper structure.

While an illustrative form of the invention has been disclosed in considerable detail, it will be understood that various changes may be made in the construction and arrangement of the various parts without departing from the general principles and scope of the invention.

What we claim is:

1. An overedge sewing machine structure comprising a base having a rotary operating shaft, means carried by said base providing a horizontal work supporting surface, work performing means in said base comprising a feed dog, an overedge looper, and an under looper, said over-edge looper and said under looper being mounted for movement in parallel closely spaced planes, connections from said shaft for operating all of said work performing means, said base being adapted for selective connection with any one of a plurality of upper frame members of different form, the selected upper frame member being connected with said base and having needle supporting and operating means adapted to cooperate with said work performing means to form a seam, the needle support in said connected member being arranged for reciprocation in a plane perpendicular to said horizontal work supporting surface, said connected upper frame members and said base being separable along a plane substantially below said work supporting surface, means for connecting the selected upper frame member to said base and means for inter-connecting said shaft with the needle supporting and operating means of the connected upper frame member for operation

thereof in coordination with said work performing means.

2. An overedge sewing machine structure comprising a base having a main rotary shaft, work performing means in said base comprising a feed dog, an overedge looper, and an under looper, connections from said shaft for operating all of said work performing means, said base being adapted for selective connection with any one of a plurality of upper frame members of different form, the selected upper frame member being connected with said base and having needle supporting and operating means adapted to cooperate with said work performing means to form a seam, the needle support in said connected member being arranged for reciprocation in a plane perpendicular to said horizontal work supporting surface, said base being adapted to form with the connected upper frame member a main enclosed chamber housing portions of the driving connections from said shaft to said work performing means and said needle support, means for connecting the selected upper frame member with said base, power receiving means exterior of said chamber arranged for either direct or indirect connection with said rotary shaft, means for connecting said power receiving means with said shaft, and means for inter-connecting said shaft with the needle supporting and operating means of the connected upper frame member for operation thereof in coordination with said work performing means.

3. An overedge sewing machine having a frame comprising a base portion with a work supporting surface at its top, a second portion extending upwardly from the base and an arm extending laterally from said second portion over said work supporting surface, said base portion and second portion having inter-communicating cavities forming an enclosed chamber, said frame being divided into sections along a horizontal plane passing through said base portion substantially below said work supporting surface, means for securing the sections of said frame together to form a unitary structure, a rock shaft carried by the upper section of said frame and disposed at least in part below said work supporting surface, edge trimming means carried by said rock shaft and operating upon said work substantially normal to the plane of said work supporting surface, needle supporting and operating means mounted in the upper section of said frame, and complementary stitch forming means for producing an overedge seam and operating devices therefor mounted in the lower section of said frame.

4. An overedge sewing machine having a frame comprising a base portion with a work supporting surface at its top, a second portion extending upwardly from the base and an arm extending laterally from said second portion over said work supporting surface, said base portion and second portion having inter-communicating cavities forming an enclosed chamber, said frame being divided into sections along a horizontal plane passing through said base portion substantially below said work supporting surface, means for securing the sections of said frame together to form a unitary structure, needle supporting and operating means mounted in the upper section of said frame, complementary stitch forming means for producing an overedge seam and operating devices therefor mounted in the lower section of said frame, means including a rotary operating shaft in said lower section of the frame for driving said operating devices, a

rock shaft parallel with and driven by said rotary operating shaft carried by said upper section of the frame at least partially below said work supporting surface, and edge trimming means operated by said rock shaft.

5. An overedge sewing machine having a frame comprising a base portion with a work supporting surface and an upper member mounted on said base portion, said base portion and said upper member having intercommunicating cavities forming an enclosed chamber and being separable along a horizontal plane passing through said base portion substantially below said work supporting surface, means for securing said base portion and member together to form a unitary structure, a rock shaft carried by the upper section of said frame and disposed at least in part below said work supporting surface, edge trimming means carried by said rock shaft and operating upon said work substantially normal to the plane of said work supporting surface, a needle carrying member mounted in said upper member, a plurality of loopers and operating devices therefor mounted in said base portion, a shaft in said base portion for driving said operating devices, a shaft in said upper member for operating said needle carrying member, and connections between said shafts within said chamber for coordinating the operation thereof.

30 6. An overedge sewing machine having a frame comprising a base portion with a work supporting surface and an upper member mounted on said base portion, said base portion and said upper member having intercommunicating cavities forming an enclosed chamber and being separable along a horizontal plane passing through said base portion substantially below said work supporting surface, means for securing said base portion and member together to form a unitary structure, a needle carrying member mounted in said upper member, a plurality of loopers and operating devices therefor mounted in said base portion, a shaft in said base portion for driving said operating devices, a shaft in said upper member for operating said needle carrying member, a second shaft in said upper member disposed at least in part below said work supporting surface, a movable work trimming blade operated by said second shaft, a stationary trimming blade mounted on said base portion and cooperating with said movable blade to trim the work, and connections between said shafts within said chamber for coordinating the operation thereof.

55 7. An overedge sewing machine having a frame comprising a base portion with a work supporting surface and an upper member mounted on said base portion, said base portion and said upper member having intercommunicating cavities forming an enclosed chamber and being separable along a horizontal plane passing through said base portion substantially below said work supporting surface, means for securing said base portion and member together to form a unitary structure, a rock shaft carried by the upper section of said frame and disposed at least in part below said work supporting surface, edge trimming means carried by said rock shaft and operating upon said work substantially normal to the plane of said work supporting surface, a needle carrying member mounted in said upper member, a plurality of loopers and operating devices therefor mounted in said base portion, a shaft in said base portion for driving said operating devices, a rotary shaft in said

upper member for operating said needle carrying member, and gearing interconnecting said shafts within said chamber for coordinating the operation thereof.

8. An overedge sewing machine having a frame comprising a base portion with a work supporting surface and an upper member mounted on said base portion, said base portion and said upper member having intercommunicating cavities forming an enclosed chamber and being separable along a horizontal plane passing through said base portion substantially below said work supporting surface, means for securing said base portion and member together to form a unitary structure, a reciprocating needle bar mounted in said upper member and carrying a needle at its lower end, said needle bar having its axis inclined at an acute angle to the vertical, means for reciprocating said bar to carry the point of the needle from a position above to a position below the work supporting surface, complementary stitch forming elements carried by said base portion of the frame and arranged for movement in parallel planes, one of said elements being arranged to cooperate with said needle below the work supporting surface, the other of said elements being arranged to cooperate with said needle above said surface, and said elements being arranged to cooperate with each other at a point adjacent said surface to form overedge stitches, means including a rock shaft mounted in said upper member for trimming the edge of the work in advance of the point of stitch formation, and means including a plurality of rotary shafts mounted in said base portion and said upper member, respectively, for operating said trimming means, said needle bar reciprocating means and said complementary stitch forming elements.

9. An overedge sewing machine having work performing devices including a needle carrier having a needle movable back and forth through the work, an under edge stitch forming element, an overedge stitch forming element, work feeding devices and edge trimming means, and having at least one rotary shaft and connections therefrom for operating said work performing devices, which comprises a frame for supporting said work performing devices, said shaft and said connections, said frame having a lower section providing a work supporting surface and an upper section connected with said lower section, said lower section being adapted for connection alternatively with an upper section of different form having a needle carrier and operating connections therefor of a different character, said sections being separable along a horizontal plane substantially below said work supporting

surface and having intercommunicating cavities providing an oil-tight chamber enclosing a major portion of said shaft and said connections, said connections comprising a rock shaft carried by said upper section and having its axis substantially in the plane of said work supporting surface for operating said trimming means, and said rotary shaft having a first portion interconnected with said needle carrier and having another portion spaced longitudinally from said first portion adapted for interconnection with the needle carrier of said different form of upper section.

10. An overedge sewing machine having work performing devices including a needle carrier having a needle movable back and forth through the work, an under edge stitch forming element, an overedge stitch forming element, work feeding devices and edge trimming means, and having at least one rotary shaft and connections therefrom for operating said work performing devices, which comprises a frame for supporting said work performing devices, said shaft and said connections, said frame having a lower section providing a work supporting surface and an upper section connected with said lower section, said lower section being adapted for connection alternatively with an upper section of different form having a needle carrier and operating connections therefor of a different character, said sections being separable along a horizontal plane substantially below said work supporting surface and having intercommunicating cavities providing an oil-tight chamber enclosing a major portion of said shaft and said connections, said connections comprising a rock shaft carried by said upper section and having its axis substantially in the plane of said work supporting surface for operating said trimming means, and said rotary shaft having eccentric and concentric portions spaced longitudinally thereof within said chamber, one of said portions being interconnected with said needle carrier and the other of said portions being adapted for interconnection with the needle carrier of said different form of upper section.
